UNITED STATES PATENT OFFICE.

JOHN F. O'CONNOR, OF CHICAGO, ILLINOIS, ASSIGNOR TO WILLIAM H. MINER, OF CHAZY, NEW YORK.

SIDE CASTING.

1,290,321.

Specification of Letters Patent. Patented Jan. 7, 1919.

Application filed February 18, 1918. Serial No. 217,510.

To all whom it may concern:

Be it known that I, JOHN F. O'CONNOR, a citizen of the United States, residing at Chicago, in the county of Cook and State of Illinois, have invented a certain new and useful Improvement in Side Castings, of which the following is a full, clear, concise, and exact description, reference being had to the accompanying drawings, forming a part of 10 this specification.

This invention relates to improvements in side castings.

The object of the invention is to provide a side casting for railway draft riggings which is of great strength per unit weight of metal, which is of substantially uniform thickness throughout and at the same time free from T-sections, which is so designed that chills or feeders during the molding are rendered unnecessary, which is reversible, which provides large abutment areas, and wherein the rivet holes are ideally located for actual service conditions.

In the drawing forming a part of this specification, Figure 1 is a side elevation of a stop or side casting embodying my invention. Fig. 2 is a top plan view of the structure illustrated in Fig. 1. And Figs. 3, 4, 5 and 6 are vertical, sectional views, taken on the lines 3—3, 4—4, 5—5 and 6—6, respectively, of Fig. 1.

In said drawing, the stop casting which I have illustrated is of the tandem type having front main stop shoulder 10, front intermediate stop shoulder 11, rear intermediate stop shoulder 12, and rear main stop shoulder 13. Corresponding limiting stop shoulders 14, 15, 16 and 17 are provided to limit the movements of the followers in a well known manner. The said stop shoulders 10 to 17 inclusive are formed by extending the web *w* of the casting inwardly and outwardly in the form of vertical convolutions, as clearly appears from the top plan view shown in Fig. 2, said convolutions being faced alternately inwardly and outwardly.

The web of the casting is also extended horizontally to form an upper flange 18 which is extended to the back plane of the casting and at the bottom a similar flange 19 is formed.

In order to provide great strength in the casting and accomplish the other objects of the invention above enumerated, I provide a series of parallel, diagonally extending con-

volutions 20, 21, 22, 23 and 24. These convolutions have their adjacent ends overlapped when viewed in a vertical plane, as clearly appears from Fig. 1, and each of said diagonal convolutions 20 to 24 has the bottom 60 thereof extended to the back plane of the casting so as to form a suitable riveting area and it is of course evident that each of said diagonal convolutions 20 to 24 is open to the inner side of the casting. Each diagonal 65 convolution is extended through or across an abutment utilized for forming one or more of the main or limiting stop shoulders. In this manner, the abutting face or stop shoulder for each of the stops is reinforced 70 by upper and lower horizontally extending flanges and two diagonally extending flanges, that is to say, four strengthening flanges, two of which are horizontal and two diagonal, whereby great resistance is afforded for 75 the stop shoulders.

At their ends, each of the diagonal convolutions 20 to 24 is circularly enlarged, as indicated at 25—25, to thereby provide sufficient space for the head of a riveting tool, 80 the rivet holes being located at the ends of said diagonal convolutions, as indicated at 26. The three intermediate convolutions 21, 22 and 23 are similarly circularly enlarged 85 at their centers, as indicated at 27—27 and for the same purpose, there being provided three rivet holes 28—28 at the centers of said convolutions, as clearly indicated in Fig. 1. At diagonally opposed corners of the casting, circular depressions 29—29 are formed 90 for two additional rivets, the arrangement being such that there are six rivet holes provided in each of two substantially parallel upper and lower lines and three rivet holes 95 along a central longitudinally extending line. By this method, I provide 15 rivet holes well distributed both lengthwise of the casting and vertically thereof so as to avoid any concentration of the rivet holes or riveting areas in any single line of resistance. 100

The casting, above described, is obviously of substantially uniform thickness throughout its entirety and of substantially uniform weight per unit of length. Obviously also the casting may be reversed and used with 105 either edge uppermost, thereby minimizing the number of parts which railroads are required to carry in stock for repairs.

I claim:

1. As an article of manufacture, a side 110

casting for draft riggings, said casting being formed of a web having a series of stop shoulders therein, and a plurality of diagonally arranged convolutions extending across said stop shoulders, said diagonal convolutions being all substantially parallel.

2. As an article of manufacture, a side casting for draft riggings having the web thereof provided with a series of vertical convolutions forming main and limiting stops, said casting having also a series of diagonally arranged convolutions extending across all of said stops, said diagonal convolutions having their bottoms disposed in

the outer plane of the casting to thereby form 15 riveting areas.

3. As an article of manufacture, a side casting for railway draft riggings, said casting having the web thereof formed with a plurality of stop shoulders, there being also 20 a series of substantially parallel, diagonally extending convolutions, the ends of the adjacent diagonal convolutions overlapping in a vertical plane.

In witness that I claim the foregoing I 25 have hereunto subscribed my name this 7th day of Feb. 1918.

JOHN F. O'CONNOR.
